(57) **CLAIM**

The ornamental design for an apparatus for thermotherapy and cold treatment, as shown.

DESCRIPTION

FIG. 1 is a perspective view of an apparatus for thermotherapy and cold treatment in accordance with the present design;

FIG. 2 is a top plan view thereof;

FIG. 3 is a bottom view thereof;

FIG. 4 is a front elevational view thereof;

FIG. 5 is a rear elevational view thereof;

FIG. 6 is a left side elevational view thereof; and,

FIG. 7 is a right side elevational view thereof.
